UNITED STATES PATENT OFFICE.

ARTHUR F. CONERY, JR., OF NEWARK, NEW JERSEY.

SOAP ARTICLE.

979,381.

Specification of Letters Patent.

Patented Dec. 20, 1910.

Application filed February 18, 1907, Serial No. 357,929. Renewed May 11, 1910. Serial No. 560,732.

To all whom it may concern:

Be it known that I, ARTHUR F. CONERY, Jr., a citizen of the United States, residing at Newark, in the county of Essex and State of New Jersey, have invented a certain new and useful Improved Soap Article; and I do hereby declare the following to be a full, clear, and exact description of the same, such as will enable others skilled in the art to 10 which it appertains to make and use the same.

This invention relates to soap articles; and consists in a soap article adapted for use as a shaving stick and like purposes, said article comprising a plurality of wafers, disks or other thin pieces of soap built up to form a unitary mass or stick having considerable lateral strength and stiffness and adapted for use as a whole but with such wafers retaining their individuality and adapted for successive use while still forming a part of such unitary mass; all as more fully herein-after set forth and as claimed. While other wafers or leaves of other materials may be 25 built up into unitary masses in like manner, I shall here describe this invention as applied principally to the manufacture of a soap article, such as a shaving stick.

Shaving sticks as customarily made consist merely of a cylindrical cake of soap. In use, this cake has an end face moistened and rubbed over the face to leave a layer of soap thereon as a preliminary to the production of a coating of lather for shaving. Commercial soaps contain large percentages of water and in a cake of this kind used in this way the soap is more apt to dry out in time than is the case with the ordinary cake used in the ordinary way and kept moist. As the 30 qualities of commercial soaps and their composition are nicely balanced to the intended uses, this drying out of shaving soap makes it less well adapted to the production of the creamy lather desired and a stick which has been altered by exposure does not leave the right amount and quality of soap on the face when rubbed thereover. Furthermore, for 35 hygienic reasons it is not desirable to bring the same surface of soap into repeated contact with the face, or with different faces.

It is the purpose of the present invention to produce a soap article or shaving stick which shall have all the convenience of application of the ordinary integral cake for

such purposes as shaving, being strong and 55 stiff enough to be held in the hand and used like a shaving stick and which shall nevertheless be free of the stated disadvantages of such an integral cake, not drying out from long use or changing in quality and presenting a fresh surface of soap for each application. To this end I provide an article or stick built up of a number of thin layers, laminæ or strata, conveniently disk-like in shape, with each such layer of such dimensions that it will suffice for an ordinary 60 using; in using the article as a shaving stick, of such dimensions that the amount of soap will suffice for a single shave. These layers or disks I assemble together with separators 65 between them to form a unitary structure of sufficient strength for the designed purposes. It takes but a little soap for a single shave and this amount in this invention may be provided by a quite thin wafer since the 70 backing given by the separator will allow such a thin wafer to be applied. To add to the mechanical strength of the assemblage and to aid in preventing drying, I surround this assemblage of soap wafers and intervening separators with a supporting and 75 shielding casing or wrapping, preferably made in separable segments so that one wafer after another can be exposed. With this I preferably also combine a special sealing coating of paraffin or other suitable material as a further aid against evaporation 80 of the contained water of the soap.

In the accompanying illustrations I have shown certain embodiments of the described 85 invention.

In this showing: Figure 1 shows a detail side elevation and partial section of one form of my improved soap article, the size and thickness of certain parts being greatly 95 exaggerated; Fig. 2 shows a transverse section therethrough; Fig. 3 shows a detail perspective view of the separators or protectors; Fig. 4 shows a side elevation and partial section of a stick having an alternative form of casing or wrapping; Fig. 5 is a view similar to that of Fig. 4 illustrating a further alternative form of wrapping and the use of double protectors or separators between the several wafers; Fig. 6 shows a detail vertical section of part of the stick 100 shown in Fig. 5; and Fig. 7 is a view similar to that of Fig. 6 showing an alternative

form of stick in which the wafers are not dished.

In the illustration (see Figs. 1, 2 and 3) numeral 1 designates a series of soap wafers in cylindrical arrangement, each being somewhat dished for reasons hereinafter set forth; 2 designates a plurality of intervening separators or protectors, preferably of paraffined or parchmentized paper or like material; and 3 is a wrapping, or casing of paper, metal foil or other suitable substance surrounding and supporting the assembled wafers and separators.

4 is a dummy of papier mâché or like material forming the top or, in use, base of the soap stick.

5 is a layer of paraffin or like material intervening between the wrapping 3 and protectors or separators 2, and serving to unite 20 and seal the edges of the separators against entrance of air or exit of moisture and to cause the wrapping 3 to adhere and further strengthen the structure.

In forming the soap article, the alternating wafers and protectors are assembled in stick form upon the dummy 4 and are then covered with a thin coating of melted paraffin or like material, forming the layer 5. While this paraffin or like material in the 30 coating is still molten, or at least sticky, the wrapping 3 is applied.

Each of the protectors 2 as shown is provided with a raised edge or flange 6 within which the next wafer (1) and next protector (2) will nest, and for convenience in detaching each such protector from the soap stick to reveal a new and fresh layer of soap there may be on each such flange or edge 6 a projecting tab 7. These tabs may be arranged 40 in line as shown in Fig. 1, in which case, preferably, the wrapper 3 does not completely surround the soap stick, the edges of the wrapper being separated by a slot opposite these tabs. To facilitate the tearing 45 off of successive portions of the wrapper in exposing fresh and clean soap wafers, the edge of the wrapper may have in it a series of lines of division 8 where the material of the wrapping or casing has been weakened 50 by grooving, cutting, breaking off the fiber, perforating or the like so that it is easy to start a tear at such points. Or these tabs may be arranged helically as shown in Figs. 4 and 5, to facilitate the detaching of any 55 given protector and if desired the wrapping 3 may completely surround the soap stick, as also indicated in Fig. 5.

If preferred, the wrapping of the stick may be formed by winding a ribbon 9 helically about the stick, the edges of the several turns of the ribbon overlapping as shown, and provided with points of weakness 10 formed in the same manner as the lines of weakness 8, whereby the portionwise 65 removal of the outer casing is facilitated.

With the wafers dished in the manner shown in Fig. 1 several advantages result. For one thing, a rounded or coned surface is given the end of the stick at the point of application to the face, and for another the soap stick is made much stronger, lateral stresses such as those incident to using the structure as a shaving stick, being distributed from one wafer to another at any given point on the stick. With these dished 75 and, consequently, nested, wafers the shaving stick is given relatively great strength and stiffness. However, I do not confine myself to the dishing of the soap cakes in this way but may use flat laminæ or strata 80 as shown in Fig. 7; in which case the adhesion of the nested edges 6 of the separators or protectors and the strength given by the outer casing are relied upon to give the necessary degree of lateral strength and 85 stiffness. For many purposes, and particularly when the article is not to be used as a shaving stick but where it is used as a source of soap leaflets, less lateral strength is required. But even with the flat disks, 90 the article can readily be made strong and stiff enough to be held in the hand and rubbed over the face in the way customary with shaving sticks. Stiffer casings are, however, required with the flat disks than 95 with the dished wafers.

If desired, there may be two of the protectors or separators between each two successive wafers. This gives somewhat more strength and has the further advantage that 100 the separators serve more perfectly to protect the soap wafers against desiccation and contamination. Upon detaching one separator with whatever soap remains after using a wafer, the next wafer below is left 105 protected by the second separator until such time as it is desired to use it. This structure is shown in Figs. 5 and 6 in which 11 designates the second protector. Each such protector or separator 11 will customarily 110 have adhering to it the adjacent wafer of soap; such adhesion being easy to produce by selecting a proper grade of paper for the separator, or by other means which will readily suggest themselves to those skilled 115 in the art; as, for example, the use of a thin coating of adhesive. But ordinarily a proper grade of paper will sufficiently adhere to the soap when pressed thereagainst. The tabs 7 of corresponding separators or 120 protectors 2 and 11 will ordinarily be used in register, as indicated in Figs. 5 and 6.

In the described structures, each layer of soap being entirely sealed away from the air and from contamination there is no possibility of injury, and although the structure as a whole is unitary and can be used with as much freedom and ease as the ordinary integral shaving stick, yet each such wafer as it is successively exposed is to all intents a 130

fresh body of soap, having all the properties of a fresh cake of soap.

While other waferlike articles can be assembled into a single unitary structure in the manner described for soap wafers, yet I regard my invention as particularly adapted to and advantageous for soap wafers.

What I claim is:—

1. A soap article comprising a series of waferlike bodies of soap, a series of separators between, covering and separating adjacent surfaces of said waferlike bodies and in contact therewith, said separators and waferlike bodies fitting together to form a sticklike body, and an enveloping covering closely adhering to the exposed edges of the separators, sealing in the waferlike bodies and uniting the assembled objects into a unitary mass.

20 2. A soap article comprising a series of waferlike bodies of soap, a series of separators therebetween, and an enveloping coating of impervious sealing material closely adhering to the exposed edges of the assembled objects and uniting said assembled objects into a unitary mass.

30 3. A soap article comprising a series of waferlike bodies of soap, a series of separators therebetween, an enveloping coating of impervious sealing material closely adhering to exposed edges and uniting the assembled objects into a unitary mass, and an outer wrapping.

35 4. A soap article comprising a series of waferlike bodies of soap, a series of separators therebetween, a covering of plastic material adhering to exposed edges and uniting the assembled objects into a unitary mass, and an outer wrapping.

40 5. A soap article comprising a series of waferlike bodies of soap, a series of separators therebetween, a covering of paraffin closely adhering to exposed edges and uniting the assembled objects into a unitary mass, and an outer wrapping.

45 6. A soap article comprising a series of waferlike bodies of soap, a series of flanged separators between, covering and separating adjacent surfaces of said waferlike bodies and in contact therewith, the flanges of the separators extending over edges of said waferlike bodies, sealing means for making a tight joint between adjacent edges of said flanged separators and uniting the assembled objects into a unitary mass, and a surrounding casing for said mass.

50 7. A soap article comprising a series of waferlike bodies of soap, a series of flanged separators between, covering and separating adjacent surfaces of said waferlike bodies and in contact therewith, the flanges of said separators covering over the edges of said waferlike bodies and successive separators being nested the one within the other, whereby waferlike bodies and separators unite to

form a sticklike body, sealing means for making a tight joint between adjacent edges of said separators and uniting the assembled objects into a unitary mass, and a surrounding casing for said mass.

70 8. A soap article comprising a series of waferlike bodies of soap, a series of flanged separators between, covering and separating adjacent surfaces of said waferlike bodies, the flanges of said separators covering the edges of said waferlike bodies and extending to and beyond the bottom edge of the next separator in series, means for closing the joints between the edges of the flanges and said bottom edges, and a casing surrounding the assembled objects.

75 9. A soap article comprising a series of waferlike bodies of soap, a series of flanged separators between, covering and separating adjacent surfaces of said waferlike bodies, the flanges of said separators covering the edges of said waferlike bodies and extending to and beyond the bottom edge of the next separators in series, means for closing the joints between the edges of the flanges and said bottom edges, and an outer wrapping pressing upon said flanges.

80 10. A soap article comprising a series of waferlike bodies of soap, a series of flanged separators between, covering and separating adjacent surfaces of said waferlike bodies, the flanges of said separators covering over the edges of said waferlike bodies and said separators being nested, a coating of sealing material closing the spaces between adjacent edges of said separators, and an outer wrapping.

85 11. A soap stick comprising a series of waferlike bodies of soap, a series of separators between, covering and separating adjacent surfaces of said waferlike bodies, said waferlike bodies and said separators being shaped to fit together into a sticklike body, sealing means circumferentially sealing, covering and uniting adjacent edges of the assembled objects, and enveloping means surrounding said sticklike body and assisting in uniting said assembled objects into a unitary mass.

90 12. A soap article comprising a series of waferlike, dished bodies of soap, a series of separators between, covering and separating adjacent surfaces of said waferlike bodies, means fastening together the assembled objects as a unitary mass and enveloping means surrounding said mass and united thereto.

95 13. A soap stick comprising a series of waferlike, dished bodies of soap and intervening separators, sealing means uniting exposed edges and converting the assembled objects into a unitary mass, and a wrapping.

100 14. A soap article comprising a series of waferlike bodies of soap, a series of tabbed separators therebetween having projecting

tabs, and means for fastening together the assembled objects to form a unitary mass.

15. A soap article comprising a series of waferlike dished bodies of soap, a series of tabbed separators therebetween having projecting tabs; successive tabs being helically arranged, and means for fastening together the assembled objects to form a unitary mass.

16. A soap article comprising a series of waferlike dished bodies of soap, a series of separators therebetween, said separators having projecting tabs and successive tabs being helically arranged, means for fastening together the assembled objects to form a unitary mass, and a wrapping.

17. A soap article comprising a series of waferlike bodies of soap, a series of separators therebetween, there being two such separators between each adjacent pair of waferlike bodies and each such separator adhering to the waferlike body next thereto, such waferlike bodies and separators being shaped to fit together into a sticklike body, and means fastening together the assembled objects as a unitary whole.

18. A soap article comprising a series of waferlike dished bodies of soap, a series of separators therebetween, there being two such separators between each adjacent pair of waferlike bodies and one such separator adhering to the waferlike body next above,

and means fastening together the assembled objects as a unitary whole.

19. A soap stick comprising the combination of a dummy base, a series of waferlike bodies of soap, and a series of separators between adjacent waferlike bodies, said objects being assembled to form a sticklike body, a coating of plastic material surrounding exposed edges in said assemblage of waferlike bodies and separators and an enveloping wrapping surrounding said assemblage and coöperating with said plastic material to unite said assemblage into a unitary mass.

20. A soap stick comprising the combination of a dummy base, a series of waferlike dished bodies of soap, and a series of separators between adjacent waferlike bodies, said objects being assembled to form a sticklike body, a coating of plastic material surrounding exposed edges in said assemblage of waferlike bodies and separators, and an enveloping wrapping surrounding said assemblage and coöperating with said plastic material to unite said assemblage into a unitary mass.

In testimony whereof I affix my signature in the presence of two witnesses.
